[57] **CLAIM**

The ornamental design for a pawl latch assembly for
 securing hinged panels together, as shown.

DESCRIPTION

FIG. 1 is a left side elevational view of one embodiment
 of a pawl latch assembly for securing hinged panels
 together embodying my design;

FIG. 2 is a top plan view thereof;

FIG. 3 is a front elevational view thereof;

FIG. 4 is a rear elevational view thereof;

FIG. 5 is a bottom plan view thereof;

FIG. 6 is a top plan view of a second embodiment of a
 pawl latch assembly for securing hinged panels together
 embodying my design;

FIG. 7 is a top plan view of a third embodiment of a
 pawl assembly embodying my design;

FIG. 8 is a top plan view of a fourth embodiment of a
 pawl latch assembly for securing hinged panels together
 embodying my design;

FIG. 9 is a top plan view of a fifth embodiment of a
 pawl latch assembly for securing hinged panels together
 embodying my design;

FIG. 10 is a top plan view of a sixth embodiment of a
 pawl latch assembly for securing hinged panels together
 embodying my design; and,

FIG. 11 is a top plan view of a seventh embodiment of
 a pawl latch assembly for securing hinged panels together
 embodying my design.
